OIL WELL CEMENTING PLUG

Fred Maines, Long Beach, Calif.

Application December 29, 1937, Serial No. 182,195

10 Claims.

(Cl. 166—1)

My invention relates generally to the art of cementing oil wells as a protection against the seepage and flow of water into the well hole, and more particularly to the plugs that are positioned below and on top of the cement as the same is forced downward into the well.

The principal objects of my invention are to generally improve upon and simplify the construction of the existing forms of cementing plugs, and to provide a construction that will be effective in producing improved and beneficial results in the cementing operations, particularly the keeping of the cement and fluid entirely separate from each other while the cement is being forced downwardly through the casing, and until such time as it is discharged from the lower end of the casing into the well hole, and further, to provide the lower one of the plugs which has a passageway to permit the cement to discharge downwardly through the plug, with a barrier that normally prevents the flow of cement downwardly through the plug, but which barrier may be ruptured or broken under a predetermined degree of pressure applied to the cement by the pump at the top of the well while the bottom plug rests on the float-shoe or other obstruction at the lower end of the casing.

A further object of my invention is to provide well cementing plugs of the character referred to that will cooperate so as to enable the cement to be conveniently and economically delivered through the casing to the point where the cementing of the well is to be accomplished, and the cement then being forced under pressure through the lower one of the plugs and the float-shoe that is carried by the lower end of the casing into the annular space within the well hole around the casing so as to provide a concrete wall surrounding the well hole throughout the area through which water flow or seepage would otherwise occur.

With the foregoing and other objects in view, my invention consists in certain novel features of construction and arrangements of parts that will be hereinafter more fully described and claimed and illustrated in the accompanying drawing in which:

Fig. 1 is a vertical section taken through the lower portion of a well hole, with the casing positioned therein and showing my improved cementing plugs positioned within said casing and with the lower plug resting on the float-shoe that is carried by the lower end of the casing.

Fig. 2 is a side elevational view partly in sec-

tion, of a modified form of the upper one of the plugs.

Fig. 3 is a detail section taken through the upper portion of a modified form of the lower plug.

Fig. 4 is a vertical section taken through the lower portion of a modified form of the upper plug and also the upper portion of a modified form of the lower plug.

Referring by numerals to the accompanying drawing which illustrates a preferred embodiment of my invention, 10 designates the well casing that occupies the well hole W, the lower end of the casing being detachably connected to a conventional float-shoe S provided with the usual axial opening O.

The lower plug, designated by the numeral 11, is substantially cylindrical in form and constructed of wood, metal, rubber or composition. The diameter of this plug is slightly less than the internal diameter of the well casing, and the length of the plug is somewhat greater than its diameter. The lower end of the plug 11 is slightly tapered, as designated by 12, in order to permit the marginal portion of the packing disc 14 carried by the lower end of the plug to flex upwardly as a result of contact with the wall of the casing as the plug passes downwardly therethrough, and extending axially through the plug is a bore or opening 13.

Secured in any suitable manner to the under face of the plug 11 is a packing disc 14 preferably formed of flexible or semi-flexible material, for instance leather or composition, and the edges of this disc are adapted to engage the inner face of the casing as the plug moves downwardly therethrough.

Formed in the center of this packing disc is an aperture 15 that coincides with the axial bore or opening 13 through plug 11.

Overlying the upper end of plug 11 is a section 40 or sections 16 of thin material, preferably heavy fabric such as canvas, or this member may be leather, composition, or in some instances thin sheet metal such as tin, aluminum, copper or the like.

Instead of utilizing a barrier of fabric, leather, sheet metal or the like, the barrier may take the form of a valve having means associated with it to normally maintain it in closed position, and which will open only under a predetermined degree of pressure.

Overlying this member 16 is a packing disc 17 that is practically identical with the disc 14, and being formed of flexible or semi-flexible material such as leather or composition, and the edge of 55

this disc engages the inner face of the casing as the lower plug moves downwardly therethrough.

Formed in the center of packing disc 17 is an aperture 18 that coincides with the axial bore 13 in plug 11. Suitably secured on top of the packing disc 17 is a disc 19 that is somewhat smaller in diameter than the packing disc 17, said disc 19 being preferably formed of wood, metal composition or the like, and having formed through its center an aperture 20 that coincides with the aperture 18 in packing member 17 and the bore 13 through plug 11.

The upper plug, designated by numeral 21, comprises a solid cylindrical body preferably formed of wood, the diameter of which is slightly less than the internal diameter of casing 10 and the length of the plug being somewhat greater than its diameter. The lower end of this plug is slightly tapered as designated by 22, and suitably secured on both upper and lower ends of the plug are packing discs 23 of flexible or semi-flexible material such as leather, composition or the like, and the marginal edges of these packing discs bear against the inner face of the casing as the plug moves lengthwise therethrough.

Applied to the under face of the lower one of the packing members 23 and concentric therewith is a ring 24 of wood, metal, composition or the like, and which is securely fastened to the lower end of the plug.

Suitably secured to the upper end of plug 21 and overlying the intermediate portion of the upper packing member 23 is a concentrically arranged disc 25 that is slightly smaller in diameter than said upper packing member, and thus only the marginal portion of the upper packing member functions to close and pack the joint between the upper end of the plug and the inner face of the casing.

In Fig. 2 I have illustrated a modified form of upper plug 21, and in such construction the ring 24 at the bottom of the plug and the disc 25 at the upper end thereof are eliminated and the packing members 23 are secured to the end faces of the plug by fastening devices such as nails, screws or the like.

In the modified construction illustrated in Fig. 3, the perforated disc 20 is eliminated and the flexible member 17 is secured directly to the upper end of the plug 11 by nails, screws or the like, and said disc overlying the member 16.

In the modified construction illustrated in Fig. 4, the disc 19 that is applied to the upper end of the lower plug 11 is provided with a centrally arranged tapered aperture 26 that functions as a seat for a tapered plug 27, which latter projects from the lower end of the upper plug 21.

In the use of my improved cementing plugs, plug 11 is placed in the upper end of the casing and cement is pumped into the casing on top of said plug, with the result that the plug and cement are forced downwardly through the casing and all mud and liquid in front of or below the plug will be forced downwardly through the casing and discharge through the lower end thereof through opening O in float-shoe 5. This mud and liquid will be forced upwardly through the annular space surrounding the lower portion of the casing. After the required amount of cement has been delivered into the casing, the upper plug 21 is placed in the casing on top of the cement and mud or liquid is now pumped into the casing above the upper plug 21, thus forcing the two plugs with the interposed body of cement

downwardly through the casing until the lower end of the lower plug rests on the float-shoe or other obstruction.

During this downward movement of the plugs and cement, the packing members 14 and 17 scrape the inner surface of the casing thereby removing practically all mud that might otherwise adhere thereto, and the packing members 23 carried by the upper plug scrape the inner surface of the casing to remove any cement that might adhere thereto.

During the downward travel of the plugs and interposed body of cement through the casing, the member 16 functions as a barrier to effectively prevent the cement between the plugs from passing downwardly through the lower plug and mixing with the mud and liquid below said lower plug.

When the lower plug 11 rests upon the float-shoe or other obstruction, such condition will be indicated on the pressure gauge of the pump and the operation of the pump is continued to build up pressure in the mud or fluid in the casing above the upper plug, and when a predetermined degree of pressure has been delivered that portion of the member 16 that closes the upper end of opening 13 in the lower plug will be ruptured, thereby bringing about a drop in the pressure which condition will show on the pressure gauge associated with the pump and thus the pump operator will know that the member 16 has been ruptured so as to permit the cement to pass downwardly through the opening in the float-shoe.

Continued operation of the pump develops sufficient pressure to expel said cement through the opening 13 in the lower plug and through the opening in the float-shoe, and this cement will be forced upwardly through the annular space surrounding the casing, and which action elevates the mud and liquid previously expelled from the lower portion of the casing and thus provides a cement wall around the casing that keeps water from seeping into the protected portion of the well hole.

As the cement is forced upwardly in the well hole around the casing and drives the mud or fluid upwardly, a practically definite separation of the cement, mud and fluid is produced and maintained, due to the difference in the specific gravities of the mud or fluid and the cement, the latter being considerably heavier than the mud or fluid.

An especial advantage of my improved cementing plugs is that the member 16 that is carried by the lower plug forms a barrier that keeps the cement pumped into the casing, entirely separate from the mud or water below the plug and within the well hole surrounding the casing.

Obviously, the barrier member 16 may be formed of any material that will rupture under a predetermined degree of pressure and as a result, the plugs may be used under any and all conditions regardless of the depth at which the cementing-off job is accomplished, and likewise regardless of the amount of cement required for accomplishing the desired results.

As a valve is used in the place of the barrier 16, said valve may be of the type that is normally held in closed position by a spring, and which latter is of such size and tension as to yield only under a predetermined pressure.

When all of the cement has been expelled through the lower plug, the lower end of the upper plug or the ring 24 carried thereby will rest

directly on top of the lower plug or the disc 19 carried thereby, thus providing a fluid-pressure tight joint between the two plugs and the joints between the ends of both plugs and the casing 5 are sealed by the packing members 14, 17 and 23 that are carried by the ends of the plugs.

Where the modified construction illustrated in Fig. 4 is provided, the tapered member 27 that projects from the lower end of the upper plug 10 functions as a valve to engage the inclined seat of opening 26 in member 19 positioned on top of the lower plug, thus providing an effective seal between the adjacent ends of the two plugs.

Thus it will be seen that I have provided oil well 15 cementing plugs that are relatively simple in construction, inexpensive of manufacture and very effective in performing the functions for which it is intended.

It will be understood that minor changes in the 20 size, form and construction of the various parts of my improved oil well cementing plugs may be made and substituted for those herein shown and described without departing from the spirit of my invention, the scope of which is set forth in 25 the appended claims.

I claim as my invention:

1. A well cementing plug provided with a passageway for mud, fluid and cement, a member 30 normally closing said passageway and adapted to rupture under predetermined degrees of pressure, and a packing disc carried by said plug.

2. A well cementing plug provided with a passageway for mud, fluid and cement, a member 35 normally closing said passageway and adapted to rupture under predetermined degrees of pressure and packing discs carried by the ends of said plug.

3. In an oil well cementing means, the combination 40 with a cementing plug and packing members carried by the ends thereof of a second plug provided with an axial opening, a rupturable member closing said opening and packing members carried by the ends of said second mentioned plug.

4. An oil well cementing plug having an axial opening, packing members carried by the ends of said plug, a rupturable member closing the opening through said plug and a ring secured to 45 said plug and overlying the packing member that overlies said rupturable member.

5. Cementing plugs for oil wells comprising a plug having a passageway for mud, liquid and

cement, a rupturable member closing said passageway and capable of being ruptured under predetermined degrees of pressure, a plate secured to the plug and overlying said member, said plate having an aperture that coincides with the passageway in the plug and a member projecting from one end thereof and adapted to enter and close the aperture in the plate that is carried by the first mentioned plug. 5

6. A cementing plug provided with an axial 10 duct for the passage of mud, liquid and cement, means normally closing said duct and adapted to rupture under a predetermined degree of pressure and a member overlying said duct-closing means and provided with an aperture that registers with the duct through said plug. 15

7. A cementing plug provided with an axial duct for the passage of mud, liquid and cement, means secured to one end of said plug for normally closing said duct and adapted to rupture 20 under a predetermined degree of pressure and means carried by said plug for packing the joint between said plug and the casing in which said plug is positioned.

8. The combination with a cementing plug having a duct for the passage of mud, liquid and cement and means normally closing said duct and adapted to rupture under a predetermined degree of pressure, of a second plug adapted to be positioned in the well casing above the first-men- 30 tioned plug. 25

9. The combination with a cementing plug having a duct for the passage of mud, liquid and cement and means normally closing said duct and adapted to open under a predetermined degree of 35 pressure, of a second plug adapted to be positioned in a well casing above the first-mentioned plug and means for packing the joints between said plugs and the casing in which they are positioned. 40

10. The combination with a cementing plug having a duct for the passage of mud, liquid and cement and means normally closing said duct and adapted to open under a predetermined degree of pressure, of a second plug adapted to be 45 positioned in a well casing above the first-mentioned plug, means for packing the joints between said plugs and the casing in which they are positioned and means for producing a fluid pressure tight joint between the upper end of the lower 50 plug and the lower end of the upper plug.

FRED MAINES.
